UNITED STATES PATENT OFFICE.

HORACE G. BIRD, OF CHICAGO, ILLINOIS.

RAILWAY-CAR.

SPECIFICATION forming part of Letters Patent No. 436,031, dated September 9, 1890.

Application filed May 16, 1890. Serial No. 351,997. (No model.)

To all whom it may concern:

Be it known that I, HORACE G. BIRD, a citizen of the United States, residing at Chicago, in the county of Cook and State of Illinois, have 5 invented a new and useful Improvement in Railway-Cars, of which the following is a specification.

My invention relates particularly to improvement of the truck portion of a car, or 10 at least to that portion of a car which is provided between the car-body and wheels; and while features forming my improvements are applicable to railway-cars generally, I have especially designed my improvements for the 15 betterment of street-cars, and also especially for the species of self-propelling street-cars, including such as have their running-gear actuated by cable or by electric or other motor service.

20 Among the more important objects of my improvement are to provide a construction of the truck or running-gear which shall permit all the parts not of necessity connected rigidly to yield in such directions as will tend 25 to prevent undesirable strain tending to disorganize or distort the truck; to prevent the excessive longitudinal oscillatory or rocking motion common to street-cars in which the body portions materially exceed in length 30 that of the wheel-bases; to enable the tie-bar commonly employed on each side of the car for connecting together the journal-box posts thereon to be dispensed with; to avoid any rigid connection between the truck-frame and 35 car-body, whereby the latter shall depend for stability upon its weight, and may, without requiring bolts or other devices to be first loosened or removed for the purpose, be lifted from the truck to remove it from the latter, 40 and, in a similar manner, to enable the truck-frame to be lifted off the journal-boxes, enabling the common operations of removing wheels and journal-boxes to be performed without requiring first the undoing of any 45 bolts, and this with the utmost readiness, and, finally, to render the seating of the free end of the motor provided as a means of locomotion on the car elastically yielding and self-adjusting.

50 A further object is to provide a generally-improved construction of railway-car.

In the accompanying drawings, Figure 1 is

a broken plan view of the running-gear portion of a street-car provided with my improvements, but showing only one side of the 55 two similarly-constructed sides of the truck-frame. Fig. 2 is a view in side elevation of the same, showing, in addition, the line of the base of the car-body; Fig. 3, a section taken on the line 3 3 of Fig. 2, viewed in the 60 direction of the arrows and enlarged and partly broken; Fig. 4, a broken sectional view taken on the line 4 of Fig. 1, viewed in the direction of the arrow and enlarged; Fig. 5, a section taken on the line 5 of Fig. 4, and 65 viewed in the direction of the arrow; Fig. 6, a broken view in elevation showing one of the four corners of the truck-frame and car-body with the interposed spring, indicated only by dotted lines in Fig. 2; and Fig. 7, a 70 similar view of the same, showing a modification.

The wheels *w* and their axles *v*, and also the interior structure or arrangement of the journal-boxes *t*, may involve any suitable or well-known construction, though the journal-boxes should be provided with wing-pieces *t'*, to support the spring-seats *t*, Fig. 3, containing annular openings *t*², extended downward to form bearings or laterally-confining means 85 for the posts *A*. These posts form part of the truck-frame *B* and extend through the annular bearings *t*³, with reference to which they have sufficient clearance to afford to the posts and truck-frame (under control of the springs, 85 hereinafter described) easy elastic lateral movement independently of the journal-boxes *t* supporting them. Such clearance, however, is not sufficient to allow the journal-boxes *t* to be forced so far in any direction out of 90 their proper perpendicular relation to the truck-frame *B* as to endanger the stability of the truck, the intention in regard to which is to confer a degree of stability equaling that afforded with the so-called "pedestal" gear, 95 (a kind of running-gear in which the journal-box is held in its proper relation to the truck-frame by a horn-plate or pedestal external to the springs,) and also to confer the elasticity 100 which is characteristic of the so-called "post" gear (in which the journal-box is held in proper relation to the truck-frame by a vertical rod or post passing through the springs and attached at its upper end to the truck-

frame and at its lower end to the tie-bar) while dispensing with the horizontal tie-bar and its braces, which are necessary to the last-named or post gear, and with the horn-
5 plate or pedestal external to the springs necessary to the first-named or pedestal gear.

The truck-frame B may be formed of wood or of metal, or both, and the sides and ends thereof, as well as the means for securing
10 them together, may for the purposes of my improvement be of any usual or desired construction. I prefer, however, the following-described construction for the truck-frame: For each side or "wheel-piece" two lengths
15 of channel-bar r are placed back to back, with the web portion of each vertical and a filling r' of wood between them, the purpose of the latter being, first, to act as a cushion to deaden any blows (as also the ringing sound
20 thereof) to which the metal of the frame may be subjected, and, secondly, to enlarge the cross-sectional area of the wheel-piece, thereby affording the greater resistance to torsional strain and the greater horizontal surface for
25 seating parts, hereinafter described, connected with the posts A, as also any other attachments, and for applying bolts and other fastenings employed in the construction of the truck. For each of the opposite ends of
30 the frame B, I employ a channel-bar r^2 , so placed as to dispose its web horizontally, and I connect the sides and ends in the corners of the frame by means of gussets r^4 , secured by rivets r^5 , and bolts r^6 , the purpose
35 of the gussets being to confer angular stiffness to the frame and cause it to maintain its rectangular shape under all conditions. Each post A, which should be hollow, as shown, is provided between its extremities with lateral
40 flanges p and p' , affording between them about the post a countersink or recess p^2 to receive the sides of the truck-frame B, which thus embrace the post between the said flanges, and are secured together and to the
45 posts by bolts or rivets q . The under side of the flange p forms a cap for the upper end of a spiral spring o , confined between it around the post, and the annular seat t^2 in a wing t' of a journal-box t . The flange p' is formed
50 on its upper side into a cap to receive the lower end of a spring o' , surrounding the post like the spring o , and confined between the cap p' and a deeper cap n surmounting the post to envelop the spring throughout a considerable
55 extent of its length and affording upon its flat top a bearing for the base of the car-body C. The springs o and o' on each post are, for a purpose hereinafter stated, differential in strength, the lower being the stronger or
60 heavier and the upper the weaker or lighter.

Extending from side to side of the frame B, each in proper position to afford a support for the so-called "free" end of an electric motor, (not shown, as it forms no part of my invention, and may involve any suitable or well-known construction,) in contradistinction to the opposite working end, which is suitably

connected with and supported by an axle v , is a beam m . Two such beams are shown, each being intended to support the free end 70 of a motor, of which two are supposed to be provided on the car for propelling it. The beam m rests toward opposite ends upon the wheel-pieces r of the frame B, and is there attached by means of carriers m' and bolts 75 and rivets m^2 , Fig. 4. As only one of the beams m may be employed, and as both of those shown to be provided and the parts they carry and supporting them are alike, but one need be herein definitely described. 80 From the beam m depends a hanger D, the upper end of which is bifurcated, as shown, to embrace the beam laterally, on the upper side of which it is supported by a roller l' , journaled, as in the manner illustrated, in the 85 bifurcated end of the stem l , whereby the hanger may have a free traversing movement lengthwise of its supporting-beam. The lower end of the stem l is provided with an adjustable stop, preferably in the form of a nut x on 90 a thread formed on the stem, and supporting on the latter a seat l^2 , convex on its upper surface to fit into a correspondingly-concave recess in the free end of the motor suspended by the hanger D. Thus by the manner described of supporting the motor when in rounding curves in the track on which the truck may be running, or from any other cause, the wheels, axle, and motor are thrown to the right or left independently of the 100 truck-frame, the free end of the motor (which hitherto has required an especial spring or the like to support it) will readily follow such movement, or in starting or stopping the truck, or in applying pressure (as the brake-pressure) to the wheels w , the latter, the axle, and the motor may be forced temporarily nearer to or farther from the point of suspension of the free end of the motor. The hanger D is adapted, owing to the convex 105 seat l^2 and convexly-curved surface of the roller l' , with which it is provided, to follow such movements of the wheels and axle to permit the free end of the motor it supports to be oscillated slightly in every direction 110 without exerting undue strain upon the truck-frame, the working parts of the truck, or the motor.

The springs o on the posts A afford, as will be seen, an immediate elastic support for the 115 truck-frame, though the elastic movement permitted by such springs, as applied, is limited in every direction to such a range as will serve effectively to break or cushion the force of the stresses incurred under ordinary conditions of traffic, but will not permit any of the moving parts to pass beyond or out of their proper mechanical relations to each other. While this limited range of elastic movement suffices for the purposes stated, it 125 is not, however, sufficient to afford the degree of comfort and ease in riding desirable in a vehicle of the kind to which my improvement relates. Accordingly, to afford such ease and

comfort I provide the springs o' lighter than the springs o , and arranged on the posts A in the manner already described, the pair of caps n for the springs o' on the posts upon each 5 journal-box being preferably connected from one post to the other by bearing-plates n' . The spring-caps n , with their deep recesses enveloping the springs o' , in conjunction with the upper portions of the posts A extending 10 inside the springs, maintain the latter in proper vertical relation to the truck-frame and car-body, while allowing easy vertical and lateral motion to the car-body independently of the truck.

15 The division of the springs to afford the separate members o and o' on each post A is primarily for the purpose of allowing the truck-frame and all its attachments, including the free end of an electric motor (or any part 20 of the gripping mechanism employed on cable-railway cars) to receive the benefit of the cushioning effect of the springs. The comparatively-limited size of the springs o below the truck-frame prevents excessive oscillatory movement of the truck-frame and its attachments, while the springs o' above the truck-frame afford the desired additional cushion to the car-body. It will be noticed, 25 however, that while the lower springs carry the truck, the lower and upper together carry the car-body. Thus being divided and differential, as stated, they permit the car-body with its load and the truck-frame with its attachments to oscillate on the springs independently of each other, and since the two 30 springs, being of different strength, have differential synchronous periods of vibration they will vibrate (under the usual conditions of street-car traffic) more or less against each other, and by such inequality in their respective vibrations the oscillation of the car-body will tend to neutralize that of the truck, and as a result obviate the excessive lengthwise 35 oscillatory or rocking motion which is common in street-cars wherein the length of the car-body materially exceeds the wheel-base. It is not necessary that the spring o' shall be located perpendicularly above its companion 40 spring o , as the truck-frame completely divides the two springs, (which may be regarded as a single spring formed in two differential parts,) and the strength and rigidity of the truck-frame are such that it is adapted properly to support a spring o' (or as many as may 45 be required or desired) at any part of its length. Thus it is especially desirable to use a spring o^2 (indicated in Fig. 2, and shown by an enlarged view in Fig. 6) with the adjacent spring o' , of which it is a counterpart, or instead of it, near each extreme end at each 50 side of the truck-frame, the more to lessen upon the latter the vertical longitudinal oscillation of the car-body, and the spring o^2 may be at the upper side of the base of the 55 car-body, as shown in Fig. 7, where it should be secured by a rod k , passing from its upper end through the cap n and car-body base or

side, and pivotally secured at its lower end to the side of the truck-frame.

Although the foregoing description sets 70 forth my invention in its application to a truck, the principle thereof may be used with equal advantage by more or less direct application of the same to the car-body without the intervention of what is generally understood under the term "truck;" or it may be applied to a truck attached, instead of more or less rigidly to a car-body, by a center-pin or the like employed for the purpose of allowing the truck (where, for example, a car is 75 mounted upon two four-wheel trucks) to rotate under the car-body to adapt it to readily pass around curves in the track upon which the car may be running.

The particular details shown and described 80 for the application of my improvements, while they best serve my purpose, so far as I am aware, may be variously changed or modified without thereby entailing departure from the spirit of my invention. Hence I do not wish 85 to be understood as intending to limit my invention to such details.

What I claim as new, and desire to secure by Letters Patent, is—

1. In a railway-car, the combination, with 90 the journal-boxes, of posts A, supported at opposite sides of the journal-bearing in each box and having springs o confined upon them, a truck-frame surmounting the said springs, and springs o' , weaker than the 95 springs o , confined upon the upper side of the truck-frame and supporting the car-body, substantially as and for the purpose set forth.

2. In a railway-car, the combination, with 100 the journal-boxes, of posts A, supported at opposite sides of the journal-bearing in each box and having springs o confined upon them, a truck-frame surmounting the said springs, through and beyond which the posts extend, springs o' , weaker than the springs 105 o , confined upon the upper side of the truck-frame and supporting the car-body, and springs o^2 between the truck-frame near its corners and the car-body, substantially as 110 described.

3. In a railway-car, the combination, with 115 the journal-boxes, of wings t' , having annular bearings t^2 , provided with spring-seats t^2 , posts A, supported in the said bearings and provided with cap-flanges p and p' , springs o , 120 confined on the posts between the said spring-seats and cap-flanges p , a truck-frame supported on the posts between the said cap-flanges thereon, springs o' , seated around the posts in the cap-flanges p' , and caps n , 125 surmounting the springs o' at their upper ends and supporting the car-body, substantially as and for the purpose set forth.

4. In a railway-car, the combination, with 130 the journal-boxes, of wings t' , having annular bearings t^2 , provided with spring-seats t^2 , posts A, supported in the said bearings and provided with cap-flanges p and p' , springs o , confined on the posts between the said spring-

seats and the cap-flanges p , a truck-frame supported on the posts between the said cap-flanges thereon, springs o' , seated around the posts in the cap-flanges p' , caps n , surmounting the springs o' at their upper ends and supporting the car-body, and a bearing-plate n' , connecting the caps n of each pair of posts on a journal-box, substantially as and for the purpose set forth.

10. 5. In a railway-car, the combination, with the journal-boxes, of posts A, supported at opposite sides of the journal-bearings in each box and having springs o confined upon them, a truck-frame B, surmounting the said springs and formed as to its sides with channel-bars r and interposed non-resonant filling r' , and as to its ends with channel-bars r^2 and springs o' , confined upon the posts above the truck-frame and supporting the car-body, substantially as and for the purpose set forth.

6. In a railway-car, the combination, with the journal-boxes, of posts A, supported at opposite sides of the journal-bearing in each box and having springs o confined upon them, a truck-frame B, surmounting the said springs and formed as to its sides with channel-bars r and interposed non-resonant filling r' , and as to its ends with channel-bars r^2 , and having corner-gussets r^4 and springs o' , confined upon the posts above the truck-frame and supporting the car-body, substantially as and for the purpose set forth.

7. In a railway-car, the combination, with the journal-boxes, of wings t' , having annular bearings t^3 provided with spring-seats t^2 , posts A, supported in the said bearings and provided with cap-flanges p and p' , springs c , confined on the posts between the said spring-seats and the cap-flanges p , a truck-frame B, formed as to its sides with channel-bars r , supported by and embracing the posts be-

tween the cap-flanges thereon and filling r' , and as to its ends with channel-bars r^2 and springs o' , seated around the posts in the cap-flanges p' , and caps n , surmounting the springs o' at their upper ends and supporting the car-body, substantially as and for the purpose set forth.

8. In a railway-car, the combination, with the journal-boxes, of a truck-frame B, supported thereon through the medium of interposed springs o , and a car-body C, supported on the frame through the medium of interposed springs o' , the car-body maintaining its position by the mere resting of its own weight, and the frame by the mere resting of its weight and that carried by it on their respective supports and being otherwise unsecured thereon, and each being readily separable from the car by lifting it from its immediate support, substantially as described.

9. In a railway-car, the combination of a truck-frame B surmounting springs o , seated on the journal-boxes and provided transversely with a beam m , carrying a hanger D, movable thereon lengthwise of the beam and adapted to support the free end of a motor, substantially as and for the purpose set forth.

10. In a railway-car, the combination of a truck-frame B, surmounting springs o , seated on the journal-boxes and provided transversely with a beam m , and a hanger D, comprising a stem l , having journaled in its upper end a roller l' on the beam, and provided at its lower end with a curved seat l^2 for the free end of a motor, substantially as and for the purpose set forth.
